UNITED STATES PATENT OFFICE.

EDWARD MELTZER, OF NEW YORK, N. Y.

HYDROCARBON VAPORIZER AND BURNER.

Application filed May 13, 1920. Serial No. 381,049.

To all whom it may concern:

Be it known that I, EDWARD MELTZER, a citizen of the United States, residing in the city of New York, borough of Manhattan, 5 county and State of New York, have invented a certain new and useful Hydrocarbon Vaporizer and Burner, of which the following is a specification.

This invention is a hydrocarbon vaporizer 10 and burner, for brevity hereinafter termed a burner, and the object of the device is to vaporize, or gasify, liquid fuels, depending upon the conditions of operation of the device and the character of the fuel employed, 15 and to burn the resulting vapor or gas. The burner is particularly adapted for operating upon crude petroleum and its distillates, such as gasoline and kerosene, although it may be used for burning any volatile liquid 20 fuel.

The device is simple in construction, easy to operate, economical to construct, durable and efficient in operation, and, in actual practice, has been proven to possess great 25 utility.

The principle of operation of the burner consists in the projection of a liquid fuel 30 against a heated vaporizing plate, by means of an agent under pressure, preferably super-heated steam, commingling the resulting product with air in a mixing chamber, and burning the resulting mixture.

The burner as a whole is novel, and, also 35 many of the elemental parts thereof, as will appear from the hereinafter detailed description of the device and its mode of operation.

In the accompanying drawings I have 40 illustrated different practical embodiments of the invention, but the constructions shown therein are to be understood as illustrative, only, and not as defining the limits of the invention.

Figure 1 is a plan view of the burner.

Figure 2 is a sectional elevation on line 45 2—2 of Figure 1.

Figure 3 is an end view of the burner, partly in section, taken on line 3—3 of Figure 2.

Figure 4 is a front view of the burner.

Figure 5 is a sectional view on line 5—5 of Figure 2.

Figure 6 is a view, partly in side elevation and partly in section, showing means for 55 operating the air shutters simultaneously,

and, also, means for automatically regulating the flow of fuel to the burner, and

Figure 7 is a front view of the burner shown in Figure 6.

Referring particularly to Figures 1 to 60 5, both inclusive, A is the main body of the burner, and, as shown, it is substantially cylindrical in form, though it may be of any desired shape and size. It is preferably made by casting and is provided near its 65 lower part with an extension, a, which forms a table or support for certain other parts of the device. The front or inlet end of cylinder, A, has a cap, b, preferably frusto-conical in shape, which cap is provided with 70 perforations, c, forming air inlets to the cylinder. Cap, b, is provided also with dampers or shutters, d, usually four in number, operated individually or collectively, whereby additional air may be admitted to 75 the cylinder other than that normally supplied thereto through perforations, c.

In order to initially ignite the vaporized fuel, cap, b, is provided with a door or opening e, preferably pivoted, as shown at f, 80 and having a handle g, for operating it.

The external end of cap, b, is substantially closed by a vaporizing plate, B, having a depression or cavity, h, therein against which liquid fuel is fed or projected, and, 85 exteriorly of said depression or cavity, there are openings, i, preferably six in number, leading into cylinder, A. C is a casing secured to plate, B, and is provided with an annular chamber, j, for receiving steam, or 90 equivalent agent, through pipe D. Chamber, j, has an outlet pipe, k, controlled by valve l, for water of condensation which may form therein when the apparatus is first started.

Chamber, j, has also a plurality of outlets, n, corresponding in number to, and in alignment with, the openings, i, in vaporizing plate, B, and in each of which is screwed a nozzle, o, entering its alining opening, i, 100 whereby steam or air admitted by chamber, j, may escape, in the form of suction jets, into cylinder, A.

Concentric with chamber, j, and screwed into casing, C, is a nipple, p, provided with 105 a cap, q, the latter having an opening into which extends an oil pipe, r, having a valve, s, controllable by handle, t, whereby liquid fuel is supplied through nipple, p, against the depression or cavity, h, in the vaporizing 110

plate, B. The spindle of valve, s , in the oil pipe is provided with a needle or pointer, w , movable across a dial, v , for indicating the extent to which the oil valve is opened.

5 Steam pipe, D, leads from a superheating coil, E, which coil is located in the path of the products of combustion from cylinder, A, said coil, E, being supplied with steam through inlet pipe, F. Pipes D and E, are held in position by clamps, x and y , respectively, cooperating with ring, c' , secured to cylinder, A, by set screws, e' .

Near the exit end of cylinder, A, is a baffle, G, shown in the form of a plate, and provided with perforations, a' , said plate being secured to the cylinder through the medium of countersunk bolts, b' . The interior of cylinder, A, has a lining of refractory material, f' , such as asbestos or fire clay, in order to protect it against melting in the event of the temperature within the cylinder rising above the melting point of cast iron.

Referring now particularly to Figures 6 and 7, I have shown means for operating the dampers, d' , simultaneously, said means consisting of hand wheel, l' , operating a rod, k' , to one end of which is secured a pinion, n' , which serves to move a circular rack, h' , provided with internal gear teeth, j' , meshing with the teeth on the pinion, n' , said rack having external teeth, i' , meshing with teeth, f^2 , on dampers, d' , and thereby serving to open or close said dampers. Dampers, d' , however, may, if desired, be operated individually by means of handles, d^2 , corresponding to the handles on the dampers, d , Figures 1 and 2. The rack, h' , is held in operative position by guides, j^2 , see Figures 6 and 7.

In Figure 6, I have shown means for regulating the feed of oil to the burner in accordance with the pressure of steam in inlet pipe, F. This result is accomplished by means of a fluid pressure regulator, H, having a diaphragm, p' , and a needle valve, a^2 , which valve controls the outlet, b^3 , of the oil inlet pipe, r' , and consequently the feed of oil to the burner through the pipe, o' . The space above the diaphragm, p' , connects with the steam pipe, F, by means of a branch pipe, s' , so that the needle valve, a^2 , is pressed downwardly to partially close the opening, b^3 , when the pressure of steam in the pipe, F, exceeds a predetermined point. Pipe, r' , is provided with valve, s' , operating handle, t' , therefor, pointer, w' , and dial, v' , the same as corresponding elements in Figure 2.

60 From the foregoing description of the apparatus it is believed its mode of operation will be clear, but it may be described, briefly, as follows: The valve in the oil pipe, r , or

r' being open, steam from any suitable source is admitted to pipe, F, passes through coil, E, pipe, D, annular chamber, j , and nozzles, o , and thence to the interior of cylinder, A, at the same time creating a suction through oil pipe, r , or r' , causing oil to be drawn up by suction through said pipe and delivered against the depression or cavity in the vaporizing plate, whence it is drawn in the form of vapor, through openings, i , into cylinder, A; the rapidly flowing current of steam and fuel vapor entering cylinder, A, causes air to enter the cylinder through perforations, c , in cap, b , resulting in the production of a mixture of steam, air and oil, or other fuel, in cylinder, A, for which reason I have termed the interior of cylinder, A, a "mixing chamber"; the mixture may now be ignited in any suitable way, as by inserting a piece of ignited waste into the mixing chamber through door, e . A very high temperature is soon produced within chamber, A, thereby serving to heat the vaporizing plate, B, and, also, the steam superheating coil, E. The baffle plate, G, serves to check the too rapid passage of the products of combustion from the mixing chamber, thereby deflecting them back to a certain extent upon the vaporizing plate, B, and heating said plate to a sufficiently high temperature to gasify the fuel projected against the cavity therein.

The invention is particularly adapted for use on all kinds of steam boilers, though it may be used in most any location in place of solid fuel. It will be noted that my system is not a gravity system, but depends on suction or exhaustion to feed the oil to the burner from a source of supply which may, if desired, be located beneath the surface of the ground, thereby insuring entire safety from explosions or other accidents.

It will be understood that the several parts of the apparatus may be made of any suitable shape and size, to adapt them to the particular conditions of operation and that minor changes may be made in the arrangement and location of the several parts without departing from the spirit of the invention.

Having thus fully described the invention, what I claim as new and desire to secure by Letters Patent is:

In a device of the class described, a mixing chamber, a perforated cap for admitting air thereto, openings in said cap separate from said perforations, a plurality of shutters or dampers for admitting air through said openings, and means for operating said shutters or dampers simultaneously.

In testimony whereof, I have signed my name to this specification.

EDWARD MELTZER.
